ELECTRIC DISCHARGE TUBE

Maximiliaan Julius Otto Strutt and Aldert van der Ziel, Eindhoven, Netherlands, assignors, by mesne assignments, to Hartford National Bank and Trust Company, Hartford, Conn., as trustee

Application April 18, 1946, Serial No. 662,969
In the Netherlands May 27, 1941

Section 1, Public Law 690, August 8, 1946
Patent expires May 27, 1961

4 Claims. (Cl. 250—27.5)

1

In the endeavours which are being made to construct discharge tubes so as to make them suitable for amplifying or generating electric oscillations of very high frequency and short waves a number of problems arise; many of these problems can be solved by reducing the dimensions of the tubes and of their various components and simplifying the circuits connected to the tubes. The use of these means eventually gives rise to the well-known tubes of small dimensions in which electrodes spaced a very small distance apart are connected to conductors which may constitute the circuits connected to the tube, use being made in this case of so-called Lecher lines.

An important problem in the construction of short-wave tubes and circuits, to which special attention has been given by the applicant, is the damping of the input circuit by the resistance and capacity connected in parallel therewith and formed by the combination of cathode and the next following electrode. The space between the cathode and the first grid, or between the cathode and the anode in the case of a diode, may be assumed to be built up from a condenser between the first grid or the anode and that side of the emitting layer of the cathode which is adjacent thereto and in series therewith a condenser and a resistance formed by the emitting layer itself; as will be established hereinafter, the properties of this layer may play an important part in a tube for short-wave purposes.

In general the opinion was held that improving results in the use of discharge tubes for short and very short waves could be attained by decreasing and decreasing the electrode spacings; researches by the applicant, however, revealed that this is not sufficient, that even in some cases disadvantages may accrue when reducing and reducing the distance from cathode to grid, or with a diode the distance from cathode to anode, without considering the emitting layer of the cathode. The researches underlying the invention revealed that it is not so much the distance from cathode to the next following electrode which should be small but that provision should be made that the ratio of the thickness of the emitting layer to the distance of the external surface of this layer from the next following electrode should be a minimum. It follows that it is not sufficient to reduce the distance of the cathode from the next following electrode but that the thickness of the emitting layer should also be a minimum. The discharge tube according to the invention and its component members

2

are proportioned in such manner that the distance of the external surface of the emitting layer of the cathode from the next following electrode is less than 0.5 mm. and the ratio of the thickness of the emitting layer to the distance just mentioned is less than 0.1. It follows that the maximum thickness of the emitting layer is 50 microns. It is, however, preferable that this thickness should be further reduced and should be less than 25 microns, very good results being attained in the use of the tubes on short wave when this thickness is less than 10 microns. The calculations and researches undertaken by the applicant show that for very short waves, that is to say decimetre and centimetre waves, the best results can only be attained if not only the distance from cathode to the next following electrode but also the thickness of the emitting layer itself are rendered a minimum, it being generally preferable for the distance of the cathode from the next following electrode to be reduced as far as possible. In connection with the use of very short waves, distances for example less than 0.25 mm. and less than 0.1 mm. are favourable.

25 It is quite true that in the literature it has been suggested that for certain reasons the emitting layer of the cathode should be chosen so as to be thin, for example thinner than 100 or even 50 microns. In practice the use of such thin layers 30 entails difficulty, particularly in manufacture, so that the use of such thin layers is very reluctantly resorted to. Researches undertaken by the applicant on the subject revealed that if tubes are to be made suitable for amplifying or generating electric oscillations of decimetre and centimetre waves it is necessary to resort to such thin layers and that it is even necessary to choose very thin emission layers, even if, for example in manufacture, certain difficulties would accrue. 35 Obviously, it is necessary to take care that the emitting layer is applied in such a manner that a very uniform layer is obtained; for this purpose the application is preferably effected by an electrolytic or cataphoretic process or again by vaporation.

40 The importance of the ratio of the thickness of the emitting layer to the spacing between the external surface of this layer and the next following electrode may be seen as follows:

45 As described hereinbefore it is possible to assume the combination of the cathode and the next following electrode to be constituted by a capacity (C_1) between the external side of the emitting layer and the next following electrode, and by a capacity (C_2) and a resistance (R_2)

formed by the emitting layer itself, as indicated by the equivalent circuit of Fig. 3.

Now, if $\omega = 2\pi f$ in which f is the frequency, the equation $\omega^2(C_1 + C_2)^2 \cdot R_2^2 \ll 1$ is generally satisfied so that the capacities and resistance here mentioned may be assumed to be replaced by the capacity C_1 and the resistance R_2 connected in series therewith. This is a condenser having a loss angle δ which angle is the complement of the power factor angle, such that

$$\tan \delta = \omega C_1 R_2 \quad (1)$$

Thus, if the combination of the cathode and the next following electrode has connected to it a circuit or Lecher line system free from loss, the quality of the circuit will be, as a result of the above-mentioned loss angle,

$$Q = \frac{1}{\omega C_1 R_2} \quad (2)$$

Now, it is generally required that the quality of the circuit should not fall below a value Q_0 , or in other words

$$\frac{1}{\omega C_1 R_2} \geq Q_0 \quad (3)$$

If A is the surface area of the cathode, d the thickness of the emitting layer, R_0 the specific resistance of this layer and a the distance of the layer's external surface from the next following electrode.

$$C_1 = \frac{A}{36\pi \times 10^{11} a} \quad \text{and} \quad R_2 = \frac{R_0 d}{A}$$

these values substituted in (3) yield

$$R_0 \cdot \frac{d}{a} \leq \frac{18 \times 10^{11}}{f \cdot Q_0} \quad \text{or} \quad R_0 \cdot \frac{d}{a} \leq \frac{60\lambda}{Q_0} \quad (4)$$

Here, d , a and λ are in cms.

It is thus apparent that among other things a small ratio d/a is important. If this ratio is equal to or less than 0.10 the tube is suitable for use for wavelengths less than 1 metre.

In order that the invention may be clearly understood and readily carried into effect it will now be described more fully with reference to the accompanying drawings in which,

Figure 1 is a horizontal sectional view of a triode structure;

Figure 2 is a schematic view of the cathode and grid elements to show the dimensional relationships, and

Figure 3 is an equivalent circuit of the electrode elements of Fig. 2.

Referring to the drawings, 1 designates the core of the cathode of an electric discharge tube, it being possible for said cathode to be heated either directly or indirectly, as by a heater 1—h, 5 2 designates the emitting layer of the cathode and 3 the next following electrode, depending upon whether the discharge tube is a triode or a diode, it being shown here for example as a triode and having an anode 4, and an enclosing 10 glass envelope 5, which may be a grid or the anode. If the tube has to be suited to the use on a wavelength of 50 centimetres and Q_0 is equal to 100, whereas R_0 is 500 ohm-cms., it is seen that the value d/a hereinbefore mentioned must be 15 equal to or less than 0.06, that is to say at a distance of 100 microns of the external surface of the emitting layer 2 from the electrode 3, as is a normal distance for tubes suitable for generating or amplifying very short waves, the thickness 20 of the emitting layer 2 cannot be in excess of 6 microns.

What we claim is:

1. An electric discharge tube for amplifying or generating electric oscillations of very high frequencies, comprising a cathode having a supporting base and a layer of electron-emitting material thereon, and an adjacent electrode closely spaced therefrom, the distance of the emitting layer of the cathode from the said adjacent electrode being less than 0.5 mm. and the ratio of the thickness of this layer to the distance just mentioned is less than 0.10.

2. An electric discharge tube as claimed in claim 1, wherein the thickness of the emitting 35 layer of the cathode is less than 25 microns.

3. An electric discharge tube as claimed in claim 1, wherein the thickness of the emitting layer is less than 10 microns.

4. An electric discharge tube as in claim 1, 40 wherein the distance of the external surface of the emitting layer from the said adjacent electrode is less than 0.1 mm.

Certificate of Correction

Patent No. 2,478,986

August 16, 1949

MAXIMILIAAN JULIUS OTTO STRUTT ET AL.

It is hereby certified that errors appear in the printed specification of the above numbered patent requiring correction as follows:

Column 4, line 10, after the numeral "5" strike out the comma; same column, line 6, beginning with the comma and word ", depending" strike out all to and including "envelope 5" in line 10, and insert the same in line 11, after the syllable "ode" and before the period;

and that the said Letters Patent should be read with these corrections therein that the same may conform to the record of the case in the Patent Office.

Signed and sealed this 27th day of December, A. D. 1949.
